Filed June 24, 1966, Ser. No. 2,804

Term of patent 14 years

(Cl. D91—3)

FIG. 2.

FIG. 1.

FIG. 3.

FIG. 4.

FIG. 5.

FIG. 1 is a plan view of a pinch valve, showing my new design;

FIG. 2 is an inverted elevational view thereof;

FIG. 3 is a bottom plan view thereof;

FIG. 4 is a sectional elevation taken along line 4—4 of FIG. 1;

FIG. 5 is a right end elevation thereof.

The left end not shown is similar to the right end. The dominant features of the design reside in the portion shown in full lines.

I claim:

The ornamental design for a pinch valve for flexible tubing and the like, as shown and described.
